Elmer J. Ney, of Lowell, Mass.
Assignor to

The Lowell Manufacturing Company,
Entered July 11, 1857. Pat'd July 5, 1857.

The schedule referred to in this Letter, Patent and making part of the same.

To all whom it may concern:

It is known, that I, Elmer J. Ney, of Lowell, in the County of Middlesex and State of Massachusetts, have originated and designed a new pattern for carpets and other fabrics, of which the following is a full, clear and exact description, reference being had to the accompanying drawings making part of this specification.

1. in the center is a small oval figure, resting on the gothic fig. 2. the interior of which is formed of small diamonds.

Surrounding the figures 1. and 2. is the oval fig. A. bordered with scrolls and extending from side to side, the group of flowers B. rest on the oval A. and lie at equal distance from the center 1.

By matching the ends another oval fig. C. is formed, overlapping and running at right angles with the fig. A. and surrounding the gothic figs. 4 and 5. the groups D. occupy a position on the fig. C. similar to that of the groups B. on the figure A. the sides E. when matched form irregular figures bordered with scrolls and sprigs.

Occupying the space between the figures A. C. & E. are the branches F.

The colors employed for the different portions of the design may be varied to suit the taste and wishes of the manufacturer.

Claim.

What I claim as my invention, and desire to secure by letters Patent, is the design or pattern for carpets herein set forth.
